UNITED STATES PATENT OFFICE

CHARLES LOUIS FLORISSON, OF COURBEVOIE, BECON-LES-BRUYERES, FRANCE, AS-SIGNOR OF ONE-HALF TO SOCIETE DE CONDENSATION & D'APPLICATIONS MECANIQUES, OF PARIS, FRANCE, A CORPORATION OF FRANCE

MOTION TRANSFORMING MECHANISM

Application filed October 30, 1929, Serial No. 403,465, and in France November 8, 1928.

The present invention has for its object a device for obtaining, from a movement of rotation of constant direction about an axis or shaft, either a reciprocating movement of 5 a member or element, or a movement of rotation of another shaft, these latter movements (reciprocating movement or movement of rotation of the second shaft) being of definite and limited amplitude with rapid return to 10 the original position of the member or shaft driven, and with automatic renewal of the two successive operations above pointed out, to wit, controlled movement and return to the original position.

15 This transforming device is essentially composed of a wire or flexible strip, stretched between two springs and wrapped about a predetermined arc of a wheel or ratchet cam driven by a driving shaft, said wire or said 20 strip being arranged during passage to be caught by each ratchet tooth, with freeing of the ratchet tooth at the extremity of the driving arc, the wire or the strip acting on the one or more members to be displaced and being 25 brought back, by the return force of one of the springs, after freeing of each tooth, to the initial position.

The following description and the accompanying drawing will enable the principle of 30 the invention and the means for establishing the device to be well understood.

Fig. 1 is a transforming device for producing reciprocating movement;

Fig. 2 is a perspective detail of a disengaging fork partially showing the same on a larger scale;

Fig. 3 is a transforming device for producing circular alternating movement.

40 Fig. 4 shows a modification of the device illustrated in Fig. 1.

Fig. 5 is a diagram illustrating the control of a plurality of reciprocable members.

Fig. 6 is a diagram analogous to Fig. 3, 45 showing the use of a plurality of pulleys.

In the drawing O represents the driving shaft turning in the direction indicated by the arrow. On said shaft is keyed a wheel A whose rim is provided with a certain number of ratchet teeth B, C, D these being three such teeth in the embodiment illustrated. Said ratchet teeth have their straight side turned in the direction of movement. 50

A wire EF stretched by two springs G, H respectively attached to fixed members I and J of the mounting of the device, is wrapped about the wheel A along an arc K, L determined in advance by the angle given by construction to the two lengths of cable EK and LF. The movable body to be driven is fixed 60 on the wire at N for example.

The springs G and H are chosen in a way that the effort of return spring G, during the whole stroke of the wire, is greater than the sum of the effort of the stretching spring H and the tangential force of friction of the wire on the wheel. The tangential force remaining tending to displace the wire to the left is less than the tangential motive force of the wheel A. 65

The wire carries at a point a small transverse rod M which is caught by the straight side of the ratchet teeth during rotation of the wheel, as shown in detail in Fig. 2, the ratchet, for example, being grooved at half width of the wheel to permit the passage of the wire. 70

A stop, for stopping the stroke of the wire towards the left, is disposed in a way that in the absence of the ratchet on the arc KL the cross-piece M occupies a position near the point K. 75

Under these conditions, during movement of the wheel A, the following operations succeed each other:

The member N being at rest in the position N₀ the origin of its movement, a ratchet tooth arriving at K seizes the cross-piece M. From this moment on the member N takes 90

rectilinear movement towards the right at a speed

$$R \frac{d\theta}{dt},$$

5 R being the radius of the wheel A and

$$\frac{d\theta}{dt}$$

- 10 its angular speed so that the movement of N is therefore controlled in a definite way by that of the driving shaft O. When the ratchet tooth and the cross-piece M arrive at the extremity L of the winding arc, the 15 cross-piece M is released from the ratchet tooth, the speed of N towards the right ceases and the cross-piece being no longer rigid with the wheel, the spring G returns the movable member to its original position from its extreme position N₁.

20 The different phases of movement above take place during passage of each ratchet tooth over the arc KL.

Instead of causing the cross piece M to 25 become disengaged only on the straight side of the ratchet tooth at L, I may limit the driving arc to a smaller value than the winding arc by disposing a fork straddle of the wheel such fork being fixed as at P (Fig. 2) 30 and inclined along the radius.

When the cross-piece M arrives in contact with the fork, it becomes clamped in the V formed by the straight side of the ratchet tooth and the inclined surface of the fork 35 thereby becoming driven outwardly which frees the same of the ratchet tooth.

I therefore have by means of the above described device the possibility of driving the movable member N in a rectilinear movement, as described at the beginning of this 40 specification.

In the case where it is desired to obtain a movement of rotation, I cause one of the extremities of the wire EF, E for example, to pass over a wheel Q of the desired 45 diameter. This result is obtained by the modification illustrated in Fig. 3.

The ratio of the radii of the two wheels is obviously chosen at will.

50 Obviously I do not depart from the scope of the invention by providing the wheel A with any number of ratchet teeth disposed equidistantly or not; by substituting therefore indentations on the periphery of the 55 wheel A; by substituting for the wire a flexible thin strip L₁ (Fig. 4), in which case the ratchet tooth A₁ may be a simple tooth and the cross-piece M can be replaced by a hole R in the flexible strip L₁; by substituting 60 for the wheel A or the wheel Q cams of a predetermined law allowing to obtain for the movable member N or the shaft of the wheel Q, controlled strokes whose movement law will be a predetermined function 65 of the advance of the motor shaft. The wire

may be given any length and its movement can be guided or deviated by grooves in fixed members or rollers. The springs can naturally be of any nature and shape provided that their elastic forces answer the definition above indicated. I may control simultaneously from a driving shaft S (Fig. 5), the rectilinear movement of several members such as N₂, N₃, N₄, connected together by the wire L₂. I may also control simultaneously 70 from a driving shaft S₁ (Fig. 6) several shafts such as T₁, T₂, carrying the wheels or cams Q₁, Q₂, on which the strip L₃ is wrapped. The motor shaft can be given a movement of constant rotation or a variable speed according to a predetermined law.

I can cite, by way of concrete example, the device above disclosed, is readily applicable to chronographs, recorders, oscillographs, serving as the marking element or the luminous ray, sounding apparatus or measurers of distance by echo, optical systems, graphic or photographic recorders and the like.

Having described my invention what I claim as new and desire to secure by Letters Patent is:

1. A mechanical movement of the type described comprising a driving shaft, a ratchet wheel on said driving shaft, flexible means extending part way round the periphery of said ratchet wheel, resilient means supporting the ends of said flexible means, means on said flexible means for engaging the teeth of said ratchet wheel and reciprocable means operatively engaged by said flexible means. 95

2. A mechanical movement of the type described comprising a driving shaft, a grooved ratchet wheel on said driving shaft, a plurality of pairs of ratchet teeth on said wheel, flexible means in said groove extending part way round the periphery of said ratchet wheel, resilient means supporting the ends of said flexible means, a cross-piece carried by said flexible means adapted to engage said pairs of ratchet teeth and reciprocable means fixed to said flexible means. 100

3. A mechanical movement of the type described comprising a driving shaft, a grooved ratchet wheel on said driving shaft, a plurality of pairs of ratchet teeth on said wheel, a flexible wire in said groove extending part way round the periphery of said ratchet wheel, resilient means supporting the ends of said wire, a cross-piece carried by said flexible wire adapted to engage said pairs of ratchet teeth and reciprocable means fixed to said flexible means. 115

4. A mechanical movement of the type described comprising a driving shaft, a ratchet wheel on said driving shaft, flexible means extending part way round the periphery of said ratchet wheel, resilient means supporting the ends of said flexible means, means on said flexible means for engaging the teeth of said ratchet wheel, means for disengaging 120

said last mentioned means from said ratchet teeth at a predetermined point on said ratchet wheel and reciprocable means fixed to said flexible means.

5. A mechanical movement of the type described comprising a driving shaft, a grooved ratchet wheel on said driving shaft, a plurality of pairs of ratchet teeth on said wheel, flexible means in said groove extending part way round the periphery of said ratchet wheel, resilient means supporting the ends of said flexible means, a cross-piece carried by said flexible means adapted to engage said pairs of ratchet teeth, a cam adapted to disengage said cross-piece from said ratchet teeth, at a predetermined point on said ratchet wheel and reciprocable means fixed to said flexible means.

6. A mechanical movement of the type described comprising a driving shaft, a grooved ratchet wheel on said driving shaft, a plurality of pairs of ratchet teeth on said wheel, a flexible wire in said groove extending part way round the periphery of said ratchet wheel, resilient means supporting the ends of said wire, a cross-piece carried by said flexible wire adapted to engage said pairs of ratchet teeth, an inclined plate adapted to disengage said cross-piece from said ratchet teeth at a predetermined point on said ratchet wheel and reciprocable means fixed to said flexible means.

7. A mechanical movement of the type described comprising a driving shaft, a grooved ratchet wheel on said driving shaft, a plurality of pairs of ratchet teeth on said wheel, flexible means in said groove extending part way round the periphery of said ratchet wheel, resilient means supporting the ends of said flexible means, a cross-piece carried by said flexible means adapted to engage said pairs of ratchet teeth, a bifurcated inclined plate extending on both sides of said ratchet wheel for disengaging said cross-piece from said ratchet teeth at a predetermined point on said ratchet wheel and reciprocable means fixed to said flexible means.

8. A mechanical movement of the type described comprising a driving shaft, a ratchet wheel on said driving shaft, flexible means extending part way round the periphery of said ratchet wheel, resilient means supporting the ends of said flexible means, means on said flexible means for engaging the teeth of said ratchet wheel and a grooved pulley engaged by a portion of said flexible means.

9. A mechanical movement of the type described comprising a driving shaft, a grooved ratchet wheel on said driving shaft, a plurality of pairs of ratchet teeth on said wheel, flexible means in said groove extending part way round the periphery of said ratchet wheel, resilient means supporting the ends of said flexible means, a cross-piece carried by said flexible means adapted to engage said

pairs of ratchet teeth and a grooved pulley engaged by a portion of said flexible means.

10. A mechanical movement of the type described comprising a driving shaft, a toothed wheel on said driving shaft, perforate resilient means extending part way round the periphery of said wheel adapted to engage the teeth thereon, resilient means for supporting the ends of said resilient means, and means on said first mentioned resilient means adapted to be reciprocated thereby.

In testimony whereof I have signed this specification.
